UNITED STATES PATENT OFFICE

AUGUSTIN F. COMEAU, OF PROVIDENCE, RHODE ISLAND

WIRE-TWISTING IMPLEMENT

Application filed July 11, 1929. Serial No. 377,508.

This invention relates to a wire twisting implement and has for its object to provide such an implement with a body portion having means for engaging the adjacent ends of a pair of wires to twist them together, the body portion having one or more operating handles projecting therefrom.

A further object of the invention is to provide the body portion with openings therein for receiving two adjacent ends of the wire to be twisted, the body being also provided with one or a pair of operating arms extending oppositely therefrom one or both of the arms being flattened and curved outwardly from the plane of its broadest face to be inserted between two adjacent parallel wires to twist them together.

With these and other objects in view, the invention consists of certain novel features of construction, as will be more fully described, and particularly pointed out in the appended claim.

In the accompanying drawings:

Fig. 1 is a perspective view of my improved wire twisting implement.

Fig. 2 is a view illustrating the wire as having been passed around two beams with its ends being engaged by my twisting implement and twisted together.

Fig. 3 illustrates those portions of the wire extending between the beams as being engaged by one of the arms of the twisting implement and by rotating the implement these wires are caused to be twisted together.

Fig. 4 is an edge view of the wire twisting implement showing the holes in the body for receiving the ends of the wires also showing one of the arms of the implement as extending between two wires to be twisted together.

Fig. 5 is a perspective view showing the wire-twisting implement as being hung on a hook in the belt of the user.

In the construction of steel frame buildings, many wires are used for reinforcing the concrete employed, which wires extend between the different beams, the bight of the wire passing around one of the beams, and the ends of the wire being twisted around the back of the other beam. Also to further tension these reinforcing wires the adjacent

parallel portions between the beams must also be twisted together. The present invention relates to an implement which is adapted to facilitate both of these twisting operations. This implement is provided with an operating handle one end of which handle is curved to engage both of the adjacent portions of the wire extending between the beams to twist these parts or portions together. Also this implement may be provided with a slot to receive a hook and so be suspended from the belt of the user when desired. My present construction of this instrument provides a central body portion through which is formed two holes or otherwise engaging members for the reception of the adjacent ends of the wire to be twisted together and I preferably employ a pair of operating arms extending laterally from this body portion of the implement whereby when the wires are passed through the holes or engaging members, it is only necessary to rotate the implement to twist the ends of the wire tightly together around the back of the beam. Also one or both of these arms are flattened at its ends and curved outwardly relative to the plane of the broad portion to be hooked between adjacent parallel portions of the wire to twist them together. And the following is a detailed description of the present embodiment of my invention and showing one construction of wire twisting implement by which these advantageous results may be accomplished:

With reference to the drawings, 10 designates the body portion of my improved twisting implement which is preferably rectangular in cross section and edgeways through the body I have formed a pair of spaced holes 11 of a size to receive the ends 14 or that size of wire which is used in reinforcing concrete work. Extending in opposite directions from this body portion are a pair of operating arms 12, each having one surface in the plane of the body, said surfaces of the two arms being on opposite sides and the other face tapering from the body toward the end and being flattened, somewhat in chisel shape at its ends, and the end extremity of this flat portion is curved outwardly from

the plane of the flattened portion as at 13, to be hooked between the two adjacent parallel wires 15, see Fig. 2, and then be rotated to twist these wire portions together, as illustrated in Fig. 3.

It is found in practice that unless the implement is flat at its engaged end, it will rotate axially in the hand of the user and will not perform its functions in a practical way.

In some instances I slot one of the arms as at 16 for the purpose of receiving a hook 17 on the belt 18 of the workman to serve as a convenient means of supporting the implement when not in use. My improved wire twisting implement is extremely simple and inexpensive in construction and is very practical in operation, and by its use I can perform two twisting operations: first, that of twisting together the ends of the wire, and secondly, twisting together the intermediate parallel strands of the wire both with the single implement.

I have herein shown two oppositely extending operating arms but, one arm only may be employed if desirable.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A wire twisting implement having a body portion of substantial width and thickness, a pair of arms of a width substantially that of the body and of a thickness less than that of said body and of substantial length extending in opposite directions from said body, the opposite faces of the two arms being in the plane of the body and their other faces being inclined from the body toward their ends, said arms being chisel-shaped at their extremities and said end portions being oppositely curved relative to each other to be readily inserted between parallel wires to twist them together.

In testimony whereof I affix my signature.

AUGUSTIN F. COMEAU.
